Frank A. Serafin, 40 Oneida Road,
Pontiac, Mich. 48053

Continuation-in-part of design application Ser. No. 7,612, June 27, 1967. This application Oct. 18, 1967, Ser. No. 9,051

Term of patent 14 years

(Cl. D22—29)

FIG. 1 is a top plan view as seen from the left side of FIG. 2, showing the flat nose portion of my new design.

FIG. 2 is a side elevational view as seen from the right side of FIG. 1.

FIG. 3 is a bottom plan view as seen from the right side of FIG. 2.

FIG. 4 is a rear end elevational view as seen from the bottom of FIG. 1.

FIG. 5 is a front end elevational view as seen from the top of FIG. 1.

FIG. 6 is a cross-sectional view taken on the line 6—6 of FIG. 1; and

FIG. 7 is a cross-sectional view taken on the line 7—7 of FIG. 1 showing the plane of the flat nose portion.

The broken lines are shown for illustrative purposes only.

This application is a continuation-in-part of my co-pending application Serial No. D-7,612 filed June 27, 1967 for a fish lure and now abandoned.

I claim:

The ornamental design for a fish lure, as shown and described.
